SCHOOL DESK AND SEAT FRAME

William James Bargen, Waukegan, Ill.

Application March 29, 1951, Serial No. 14,663

Term of patent 14 years

(Cl. D15—1)

To all whom it may concern:

Be it known that I, William James Bargen, a citizen of the United States of America, residing at Waukegan, in the county of Lake and State of Illinois, have invented a new, original, and ornamental Design for a School Desk and Seat Frame, of which the following is a specification, reference being had to the accompanying drawing, forming a part thereof.

In the drawing the figure shows a perspective view of a school desk and seat frame, showing my new design.

The broken lines depicting the seat and desk portions are for illustrative purposes only.

I claim:

The ornamental design for a school desk and seat frame, as shown and described.

WILLIAM JAMES BARGEN.
